United States Patent Office.

LOUIS J. PARSONS, OF NEW BEDFORD, MASSACHUSETTS.

Letters Patent No. 83,203, dated October 20, 1868.

IMPROVEMENT IN WHIP-SOCKETS.

The Schedule referred to in these Letters Patent and making part of the same.

To all whom it may concern:

Be it known that I, LOUIS J. PARSONS, of New Bedford, in the county of Bristol, and State of Massachusetts, have invented a new and improved Whip-Socket; and I do hereby declare that the following is a full and exact description thereof, reference being had to the accompanying drawings, and to the letters of reference marked thereon.

My invention consists in making a "whip-socket" in longitudinal sections, connected at their lower ends to each other, or to a bottom piece, by springs, hinges, or any practical device, and held together at the top by an elastic band.

Figure 1 is a perspective view of my invention, attached to a standard.

Figure 2 is a longitudinal section.

Figure 3 is a portion of standard and socket separated.

Fig. 1. A¹ is the whip-socket; B¹, standard to which the socket is attached; C¹, screw in standard; D¹, elastic band; E¹, spring-catch.

Fig. 2. A², whip-socket; B², standard; C² C², screws in standard, by which the socket is secured; D², elastic band; E², spring-catch; d², screw for securing the lower ends of sections of socket together, and to bottom piece, h²; e², nut on screw d²; g² g², springs connecting the lower ends of sections of socket.

Fig. 3. A³, portion of whip-socket; B³, portion of standard; C³, screw in standard; E³, spring-catch sliding on screws C³, having a pin on the lower end which

fits into the circular part of aperture F³, when the socket is in its proper position on the standard.

The whip-socket is secured to the carriage by pressing the heads of screws C C through the circular portion of apertures in the socket, one of which, F³, is shown in fig. 3. The socket is then pressed down, and the spring-catch E³ slips into the circular part of the aperture, and prevents the socket from rising up.

Operation.

The whip-socket being made in sections, connected at the bottom by springs or hinges, and held together at the top by an elastic band, and secured to the carriage, as herein set forth and described, its operation may be noted: The handle of the whip being pushed into the socket, the sections separate from each other sufficiently to permit it to enter, and it will be held securely by the elasticity of the band D¹.

In this invention I do not claim any device previously invented or patented for whip-socket; but

What I claim as my invention, and desire to secure by Letters Patent, is—

Making whip-sockets in longitudinal sections, connected together at the bottom by springs or hinges, and held together at the top by an elastic band, as herein set forth and described.

LOUIS J. PARSONS.
